ATTORNEY.

UNITED STATES PATENT OFFICE.

ERLO H. SWITZER, OF MOBERLY, MISSOURI.

BEDSPRING.

Application filed November 2, 1920. Serial No. 421,222.

To all whom it may concern:

Be it known that I, ERLO H. SWITZER, a citizen of the United States, residing at Moberly, in the county of Randolph and State of Missouri, have invented certain new and useful Improvements in Bedsprings, of which the following is a specification.

This invention relates to new and useful improvements in bed springs, the primary 10 object of the invention being to provide a device of this nature, which will adapt itself to the curves of the body reposing thereon, and one wherein the head portion thereof will be elevated with respect to the other 15 portions of the spring when the weight of a patient is disposed upon the springs.

Another important object of the invention is to provide a bed spring including surface lengths, the ends of which are capable of inward movement relative to the 20 spring to cause loosening of the bed lengths rendering them pliable and adaptable to the curves of a body whose weight is disposed thereon.

25 Another object of the invention is to provide means for resiliently resisting inward movement of the surface length, in order to insure the bed springs with a certain degree of resiliency.

30 Still another object of the invention is to provide a bed spring having head and foot portions capable of being arranged in an elevated position with respect to the body portion of the spring, and provide means where- 35 by only the head portion will be disposed in such relation when the weight of a patient is disposed upon the spring in the ordinary manner thereby permitting the foot portion of the spring to be disposed in approxi- 40 mately the same plane with the body portion thereof.

Other objects and advantages of the invention will become apparent during the course of the following description.

45 In the accompanying drawings, I have shown an embodiment of my invention, which is at present preferred but it is to be understood that I do not desire to limit myself to the construction, arrangement and 50 combination of the various parts shown, and that I may resort to various changes in the construction, arrangement and combination of the various parts of the invention to be hereinafter described and set forth in the 55 appended claims.

In the accompanying drawings, forming

a part of the application and wherein like numerals are employed to designate like parts throughout the several views,

Figure 1 is a side elevation of my im- 60 proved bed spring.

Figure 2 is a top plan of the same, parts thereof being broken away.

Figure 3 is an end elevation of the same.

Figure 4 is an enlarged fragmentary, lon- 65 gitudinal section of one of the side rails.

Figure 5 is a bottom plan of the same, and

Figure 6 is a transverse section of the 70 same.

Referring to the drawings, wherein for the purpose of illustration is shown the preferred embodiment of my invention, the numeral 7 designates a bed spring supporting frame in its entirety, and which consists of a pair of longitudinal spaced parallel side rails 8, the ends of which pass through clamping elements 9. Each clamping element consists of a pair of plates 10, each of which is provided with a pair of right angularly disposed sockets 11, intersecting between their ends, and extending through the ends of the plates. These plates are clamped together by means of screws 12 threaded through the web portions of the plates be- 80 tween the sockets. The ends of the side rails 8 are extended through and beyond the clamping element, where they are provided with enlargement 13. The terminal 14 of each side rail is enlarged and flattened lat- 90 erally to provide a bearing surface for an upright bearing 15. The lower end of each bearing is provided with a vertical threaded opening into which extends the shank of a screw 16 which is passed through an aper- 95 ture in the terminal 14 for securing the bearing thereto.

The supporting frame, or structure, also includes end rails 17, the ends of which are extended into the inner end of the transversely extended sockets 11 of the clamping elements and are retained therein by tightening the screws 12. In the outer end 18 of each transversely arranged socket, I clamp a self-contained spring socket pin or plunger 19, which is normally forced outwardly of the frame in order to co-operate with suitable sockets in the bed side rails for mounting the supporting frame upon the bed.

Each bearing 15 is provided with an opening which extends transversely of the bed spring, and a shaft or axle 20 is journaled

in each pair of bearings at each end of the bed spring to extend transversely thereof. The ends of each shaft 20, as most clearly seen in Figure 3, are extended beyond the bearings 15 where they are screw threaded to receive thereon upstanding arms 21. The upper ends 22 of these arms are curved outwardly of the ends of the frame, after which each arm is offset inwardly of the frame to be secured by means of bolts 23 to the ends of end rails 24 forming part of a surface structure indicated in its entirety by numeral 25.

The surface or mattress-supporting structure 25 also includes a pair of longitudinally extending spaced parallel side marginal members 26 which are capable of yielding movement. This movement is provided for by establishing yielding joints 27 in the side marginal members. These are provided about 18 inches from end marginal members 24 and the joints of one side marginal member are arranged directly opposite the joints of the other side marginal member. In order to establish the joints, each side marginal member consists of a body section 28 and two end sections 29 which are joined to the body section by a resilient strip 30. Each section has its longitudinal edges bent inwardly to be disposed in slightly spaced relation to the underface of the section, whereby a channel is formed in the section for receiving a part of the resilient bar or strip 30. As most clearly seen in Figure 5, the longitudinal bent edges of the section embrace the longitudinal edges of the resilient strip 30 in order to retain the same in engagement with the section and to prevent displacement of the strip. A bolt 31 is extended through the end of each section adjacent the joints 27, and through the resilient strip 30 for securely fastening the same to the end of the section adjacent the joints 27. Of course, in practice, the ends of the section adjacent the joints will terminate short of one another whereby two sections may move relatively at an angle and flex the resilient strip at the joint. The ends 32 of each resilient strip 30 are secured between the corresponding ends of the end marginal members 24, and the free end of a pair of the arms 22 by means of the bolt 23 extending through openings in the end of the strip.

55 A plurality of surface lengths 33 in the present instance, being chains, are secured on opposite ends to the end marginal members 24 and spaced therealong, so that the surface lengths will extend longitudinally 60 of the surface structure in spaced paralleled relation. The surface lengths are maintained in spaced relation between their ends by transversely extending coiled springs 34 connecting the same and the outermost 65 lengths to the side marginal members 28.

In order to cause surface lengths 33 to flex in a line with the oppositely disposed joint 27 at the end of the surface structure, cross bars 35 extend transversely of the structure and overlap the surface lengths, while the 70 ends of each cross bar are secured to the side marginal members 26 by one pair of the bolts 31 arranged adjacent the joint 27.

A draw-bar 36 is arranged centrally of the bed spring between the surface structure and the supporting frame to extend longitudinally thereof, and each end of the draw-bar is provided with a T-shaped head 37, the ends of which are apertured to receive therein the hooked ends of coiled springs 38. 80 The opposite ends of these coiled springs 38 are also hooked and fastened to hooks 39 connected to apertured depending portions 40 of the arms 22. These springs 38 extend from the hooks 39 at an angle to the side members 8 of the supporting frame as clearly shown in Figure 2. Relatively short coiled springs 41 have one end connected to each hook 39 and its opposite end hooked into an aperture 42 in each clamping element 9, so that these springs 41 and 38 normally urge the arms 21 outwardly of the ends of the frame to retain the surface element 33 in a taut condition.

To further assist in urging the arms 21 outwardly of the ends of the frame and to resist the inward movement of the end rails 24, when a weight is positioned upon the surface lengths 33, an inverted U-shaped arm 43 is secured to each shaft or axle 20 by the latter passing through the parallel legs of the arms between their ends. The arch of each arm 43 is secured by a bolt 44 to the intermediate portion of its adjacent end marginal member 24, and a transversely extending rod 45 extends through the free ends of the legs of each arm whereby corresponding ends of a pair of coiled springs 46 may be fastened to the rod, while the opposite corresponding ends of these springs 46 are hooked in an aperture provided intermediate the end of the end rail 17 of the supporting frame. The ends of each rod 45 are extended beyond the legs of each arm 43 and are looped whereby corresponding ends of a pair of springs 47 may be fastened to the ends, while the opposite ends of these springs are connected to the apertured end of the T-shaped head 37 at an end of the draw-bar 36.

From the foregoing description, it will be apparent that when a person lies upon the surface structure, the joint 27 adjacent his shoulder will be caused to flex downwardly, due to the fact that the heaviest portion of 125 the body is arranged nearer the upper portion thereof. The joint 27 adjacent the patient's feet will not be affected, due to the fact that there is very little weight upon the lower end of the surface structure. 130

When the joints adjacent the head of the bed flex, and weight is imposed upon the body portion of the surface structure, the arms 21 and 43 will be caused to move inwardly toward the center of the bed spring due to the fact that they are pivotally mounted by the shaft 20. The ends of the surface length 33 will be caused to move inwardly due to a corresponding movement of the end marginal members 24, and consequently the surface lengths will become loosened so that they may readily conform to the curves of a body resting thereupon. As the upper ends of the arms 22 and 43 move inwardly toward the center of the bed spring their lower ends move outwardly thereof, and consequently tension the coiled springs connected to these arms whereby the surface structure is resiliently supported. As the resilient strips 30 are weaker than the combined tension or strength of the coiled springs, it will be seen that the body portion of the surface structure will be disposed lower than the head portion and the latter will be slightly inclined when the weight of a person is disposed upon the surface structure. Consequently, the head portion comfortably supports the head of a person reposing upon the bed spring in a slightly higher elevation than if the party rested upon an ordinary flat bed spring.

The foregoing description and accompanying drawings have reference to what might be considered to be the approved or preferred form of my invention. I desire it to be understood that I may make such changes in the construction, combination and arrangement of parts, materials, dimensions, et cetera, as may prove expedient and fall within the scope of the appended claims.

Having thus described my invention what I claim as new and desire to secure by Letters Patent is:—

1. A bed spring comprising a frame, a mattress supporting structure disposed thereabove, end marginal members therefor being capable of inward movement of the spring, a transverse shaft at each end of the frame, an arm mounted on the ends of each shaft and connected to the end marginal members of the mattress supporting structure, an intermediate arm mounted on each shaft between its shaft and comprising an inverted U-shaped member, the bridge portion of each member being secured to its respective end marginal member for sup-

porting the intermediate portion thereof, a draw bar, and springs connected to the ends thereof and to said arms for resisting the inward movement of the ends of said structure.

2. A bed comprising a supporting frame including side and end rails, clamps for connecting the said side and end rails together, the ends of the side rails being extended beyond the end rails, upright bearings detachably connected to the extended ends of the side rails, a shaft journaled through the pair of bearings at each end of the frame and having its ends extended beyond the bearings and screw threaded, an upstanding arm threaded on the free end of each shaft, a mattress supporting structure detachably secured to the upright arms, and springs connecting the arms and frame.

3. A bed spring including side marginal members each composed of sections relatively movable, each section comprising a channel member, and a resilient strip fastened in the channels of said sections and adapted to bridge the sections of each side marginal member.

4. A bed spring comprising a surface structure, the end marginal members thereof being capable of inward movement, a transverse shaft at each end of said structure, arms connected to the ends of said shaft and connected to the end rails, a draw-bar, and springs connected to the ends thereof, and to said arms for resisting the inward movement of the ends of said structure.

5. A bed spring comprising side marginal members, yielding joints therein, end rails connected to said side marginal members, flexible surface lengths connecting the end marginal members, and a cross bar overlapping the surface lengths and having its ends secured to the side marginal members adjacent the joints therein.

6. A bed spring comprising side marginal members having yielding joints therein, end marginal members, spaced flexible surface lengths connecting the end marginal members, and a transverse cross strip connected to oppositely disposed sections of the side rails and arranged to overlap the surface lengths.

In testimony whereof I affix my signature in presence of two witnesses.
